BOAT CANOPY TOP

Gordon B. Hale, Waukegan, and Harry Najimian, Jr.,
Lake Bluff, Ill., assignors to Outboard Marine Corporation, Waukegan, Ill., a corporation of Delaware

Filed May 27, 1963, Ser. No. 75,077

Term of patent 14 years

(Cl. D71—1)

Fig. 4.

Fig. 5.

Fig. 6.

The dominant features of our design reside in portions shown in full lines. The boat shown in broken lines in the several views is included for illustrative purposes only.

We claim:

The ornamental design for a boat canopy top, as shown and described.
